UNITED STATES PATENT OFFICE.

AUGUST PUTSCH, OF WANNE, GERMANY, ASSIGNOR TO THE KOPPERS COMPANY, OF PITTSBURGH, PENNSYLVANIA, A CORPORATION OF PENNSYLVANIA.

COKE OVEN.

Application filed August 6, 1919; Serial No. 315,580. Renewed June 1, 1928.

My invention relates particularly to coke-ovens such as are set forth in U. S. Letters Patent 989,302, issued to me as assignee of G. Schwab, having substantially triangular flues in their heating walls; and it has for its objects the provision of an improved system of distribution of the combustion and the constituents and products of combustion, and an improved construction and arrangement of the oblique walls joining the lateral members of the heating-walls to form such substantially triangular flue, and such other objects as may be found to obtain in the structure hereinafter set forth and claimed.

In the drawings forming a part of this specification, and showing for purposes of illustration a preferred embodiment of the invention without limiting it to less than all the features of structure or operation that may be found to obtain in what is hereinafter described or claimed.

Fig. 1 shows a vertical section across the coke-oven battery, on the line 1—1 of Fig. 2; Fig. 2 shows a vertical section on the line 2—2 of Fig. 1;

Fig. 3 shows horizontal sections on the correspondingly marked lines of Fig. 2;

And Fig. 4 also shows horizontal sections on the correspondingly marked lines of Fig. 2, and is a continuation, across the battery, of the sectional view of Fig. 3.

Like reference numerals indicate like parts in all of the figures.

20, 20, 20 are the coking chambers, in series in the upper story of the battery, and intermediate the heating-walls 21, 21 which are mounted on the pillar walls 22, 22 of the lower story of the battery. Between the pillar-walls, which form the sides thereof, are located the regenerators 23, 23, each of which extends all the way through from the pusher side to the coke side of the battery, and includes, below its checker-work, sole channels 24, which extend the full length of the regenerator and open at one end into the air-box 25 and stack-flue 26 with which they are alternately connected during the alternate periods of reversal. Such connections are at alternately opposite ends of the sole channels of alternate regenerators, and such alternate regenerators are employed, during the alternate periods of reversal, for preheating the air of combustion and for absorbing heat from the products of combustion. Each regenerator 55 communicates at its top, through the ports 27,

with an adjacent series of substantially triangular flues 28, 29 in each of the adjacent heating-walls 21 laterally above such regenerator, the ports 27 passing through the tops of the pillar-walls 23 and through the spans 30 that form the tops of the regenerators and the bottoms of the coking-chambers. Each heating-wall 21 is constituted of the two series of substantially triangular flues 28, 28 and 29, 29, laterally contiguous to each other and oppositely facing the coking-chambers on either side of such heating-wall. These two series of flues, in each heating-wall, are formed by the liner-bricks 31 of the coking-chambers, which are also the sides of the heating-wall, and by the tie-bricks 32, 32 that form oblique walls across the interior of the heating-wall. An end of one of these tie-bricks enters between the liner-bricks, and the other end of such tie-brick seats against an oblique face of a tie-brick that has its end entered between the liner-bricks of the opposite side of the heating-wall, as particularly shown in Figs. 3 and 4. Such construction of the oblique members in the heating-wall, to form the substantially triangular flues, affords the possibility of providing a maximum number of such flues in each series in each heating-wall and also provides a maximum facing of liner-bricks directly presented to the heating flames of the flues, for the most direct transmission of their heat into the coking-chambers. The fuel-gas, from one or the other of the gas-mains 33, is supplied to each flue-series 28, 28 or 29, 29, through the gas-duct 34 and supplementary gas-duct 35, the latter feeding the farther portion of the duct 34 through the connecting ducts 36 (Fig. 1). At their tops, each flue 28 of one flue-series ports into a cross-flue 37 that ports into an adjacent flue 29 of the other flue-series. The two gas-mains 33 are respectively connected and alternately, during alternate reversal periods, in communication with the flue-series 28, 28 and the flue-series 29, 29 in each heating-wall. In the alternating reversal periods, all of the flues in the flue-series 28, 28 are fired simultaneously and their combustion products pass up into the cross-flues 37 and down through the flues of the other flue-series 29, 29, in each heating-wall, and vice versa. Thus during alternate reversal periods, all of the substantially triangular flues in the two series immediately contiguous to the two sides of a coking-chamber are fired simultaneously, while the two series 110

of flues contiguous to the opposite sides of the adjacent coking-chamber are having their heat maintained by downflowing combustion-products. The draft in the vertical flues is controlled by slide-bricks 38, which may be shifted through the inspection holes 39, through which also the gas-ports 40, in the bases of the flues, and the adjacent air-ports 27, may be reached. Great simplicity and effectiveness of structure and operation are attained by the described construction and the system of firing.

The invention is hereinabove described as embodied in one particular form of construction and operation, but it may of course be embodied in other form and manner within the scope of the claims hereinafter made.

I claim:

1. In a coke-oven, in combination: a series 20 of coking-chambers; intermediate heating-walls, each constituted of two parallel series of substantially triangular flues facing oppositely the coking-chambers on either side of such heating-wall, the series of such flues being respectively located on opposite sides of the longitudinal central plane of the heating wall; and cross-regenerators each communicating with all of the flues in the adjacent series in each adjacent heating-wall; each 30 flue-series being provided with gas-supply and adapted to be fired in alternation with the contiguous flue-series in each heating-wall.

2. In a coke-oven, in combination: coking-chambers; and an intermediate heating-wall comprising two series of substantially triangular flues oppositely facing the adjacent coking-chambers, said flues having their oblique walls formed by tie-bricks and their 40 face-walls by liner-bricks, each tie-brick that is seated between liner-bricks having an oblique limb and having one of its ends entered between the liner-bricks and its other end seated upon the contiguous oblique limb of

an opposite tie-brick, whereby a single thickness of tie-bricks is interposed between the liner-bricks and forms each oblique wall across the heating-wall and separating contiguous flues. 45

3. In a coke-oven, in combination: a series 50 of coking-chambers; intermediate heating-walls; each constituted of substantially triangular flues arranged in two parallel series respectively located on opposite sides of the longitudinal central plane of the heating 55 wall; and means for effecting alternate firing of the two series of flues of each heating wall; substantially as specified.

4. The coke-oven comprising oven chambers and flued heating walls adjacent thereto 60 said walls having substantially triangular flues arranged in two parallel series on opposite sides of the longitudinal central plane of the heating wall and means comprising duct connections for effecting the firing of 65 each series of flues alternately, substantially as shown and described.

5. In a coke oven, in combination: a coking chamber; a heating wall adjacent thereto, said wall being constituted of substantially triangular flues arranged in two longitudinally extending substantially parallel series; and means for effecting firing of each series alternately; substantially as specified. 70

6. In a coke oven, in combination: a series 75 of coking chambers; intermediate heating walls, each constituted of substantially triangular flues arranged in two longitudinally extending substantially parallel series, the respective series contiguous to the opposite 80 sides of a coking chamber being adapted to convey the gases in the same direction; and means for effecting alternate firing of the two series of flues of each heating wall; substantially as specified. 85

In testimony whereof, I have hereunto set my hand this 22 day of July, 1919:

AUGUST PUTSCH.
